DESIGN FOR A COMBINATION CONTAINER FOR PERFUMES

Robert B. Karoff, New York, N. Y.

Application September 21, 1937, Serial No. 71,704

Term of patent 3½ years

To all whom it may concern:

Be it known that I, Robert B. Karoff, a citizen of the United States of America, and a resident of the city, county, and State of New York, have invented a new, original, and ornamental Design for a Combination Container for Perfumes, of which the following is a specification, reference being had to the accompanying drawing, forming a part thereof.

Figure 1 is a perspective view of a combination container for perfumes showing my new design in open position.

Figure 2 is a cross-sectional view thereof in closed position.

My design as shown comprises a set of ornamental bottles, said bottles being trimmed with sombrero hats and tweed skirts and having stoppers in the form of painted heads. The container may be enclosed by placing the top in closed position as shown in Figure 2.

I claim:—

The ornamental design for a combination container for perfumes as shown and described.

ROBERT B. KAROFF.
